UNITED STATES PATENT OFFICE

JOHN H. CORDES, OF ST. LOUIS, MISSOURI

OILING SYSTEM FOR PUMPS OR COMPRESSORS

Application filed February 14, 1929. Serial No. 339,995.

This invention relates to improvements in oiling systems for pumps or compressors, and consists in the novel construction hereinafter disclosed.

An object of the invention is to provide, in connection with an air pump or compressor, an oil separating chamber having a distributing system connected therewith for lubricating the movable parts of the operating devices. The detailed advantages of the construction will be apparent from the following description, taken in connection with the accompanying drawings in which

Fig. 1 is a plan view, partially in section, illustrating the assembly of elements and certain details of construction.

Fig. 2 is a vertical section of the pump constituting a part of the combination with which the oiling system is embodied.

Fig. 3 is a perspective view of the pump.

Fig. 4 is a vertical section through the oil separating device.

Fig. 5 is another view of the same element taken on the line 5—5 of Fig. 4.

As illustrated in the drawings the system is shown as incorporated in a gas generating apparatus which is fully described in my co-pending application Serial No. 427,923.

The parts of the gas generating apparatus with which the present invention is associated comprises generally an air pressure tank 1 which the pressure is supplied by a pump 2 through a pressure line 3 that leads through an oil separator 4, the oil separator being connected with the tank 1 by a pipe 5. The pump 2 is driven by a motor 6, the motor shaft 7 being connected with the pump shaft 8 by a coupling 9. The air supply is delivered from the tank 1 to the carburetor 10 through a pipe 11, and a fuel supply is delivered to the carburetor 10 from the fuel pump 12 having a fuel supply pipe 13 and a fuel delivery pipe 14. The pipe 13 leads from a source of fuel supply, and the pipe 14 leads to the carburetor 10. The pump 12 is driven from the shaft 8 which constitutes the common drive for both the air and the fuel pumps. It is with these parts that the construction of

the present invention is primarily designed to be associated.

A suitable form of air pump is illustrated in detail in Fig. 3 of the drawings, although it should be understood that other forms of pumps may be employed in the system, if desired. The pump illustrated is of the rotary type and comprises a pump cylinder 15 having heads 16, the cylinder being supported by legs or standards 17. Within the cylinder 15 is a rotating piston 18 having a plurality of hinged wings 19 connected therewith. The piston is driven from the shaft 8 with which it is operatively connected by a cam 20. The pump is mounted in a housing 21 at the bottom of which is an oil well 22, to which oil is supplied by a filler pipe 23. Within the well 22 is a transverse wall 24 forming a sump from which oil is withdrawn through a pipe 25 that leads into the pump chamber. The oil thus drawn into the pump chamber serves to lubricate the moving parts of the pump and a portion of which entrains with the air stream and is delivered through the pipe 3 into the oil separator.

The oil separator is illustrated in detail in Figs. 4 and 5, and comprises a cylinder 26 having a bottom wall 27 and a top cover 28. The extremity of the pipe 3 connects into a threaded boss 29 on the cover 28, and the extremity of the air outlet pipe 5 connects into a threaded boss 30 likewise formed on the cover 28 but spaced from the boss 29.

A transverse downwardly extending rib 31 extends across the lower face of the cover 28 between the openings to the pipes 3 and 5. This rib serves as a baffle wall against which the incoming current of air impinges, causing gravity separation of the oil from the air, the oil accumulating in the bottom of the cylinder 26. The air passes outwardly from the cylinder through the pipe 3 freed from the entrained oil.

Within the cylinder 26 is a float 32. The float 32 has a stem 33 extending upwardly, the upper end of which operates in a recess formed in a boss 34 carried by the rib 31. The float 32 has a downwardly extending stem 35 in axial alignment with the stem 33. The lower extremity of the stem 35 is ta-

pered to form a needle valve 36 and operates to control an outlet passage 37 in a valve member 38 at the upper end of which there is a valve seat that cooperates with the needle valve 36. The outlet pipe 39 connects with the passage 37 for delivering oil from the oil separator when the oil level in the cylinder 26 reaches a height sufficient to raise the valve 36 from its seat. The purpose of maintaining a level of oil at the bottom of the cylinder 26 is to form a seal for the upper part of the chamber and to provide a body of oil for the lubricating system.

10 The pipe 39 connects with a header 40 that 15 extends across the upper part of the housing 21. A pair of tubes 41 lead from the header 40 to the bearings of the motor 6, and a tube 42 leads from the header to the operating connection between the shaft 8 and the 20 pump 12; and a pair of tubes 43 lead from the header 40 to the bearings of the pump 2. Thus there is a complete distribution of oil from the bottom of the chamber 26 to the operating parts of the motor, the fuel pump and 25 the air pump.

At the bottom of the oil wells about the motor bearings are pipes 44 that connect with a manifold 45 leading back into the housing 21, so that any excess oil is conducted 30 back into the well at the bottom of the housing 21 from the motor. Since the fuel and air pumps are within the housing 21 any excess oil drips from the bearings and operating parts into the oil well for re-circulation. 35

While the details of construction of the pump 12 are not part of the present invention, the pump has been illustrated to show its association with the drive shaft. The pump 40 receives a supply of fuel through a pipe 13 which delivers the fuel to a chamber 47. The chamber 47 is in communication with a pump chamber 48 through a passage 49. The passage 49 is controlled by an outwardly operating 45 valve 50.

In the chamber 48 is a spring operated diaphragm 51, the spring normally actuating the diaphragm to raised position. The diaphragm has a downwardly extending 50 stem 52 that is connected with a bell crank lever 53 by toggle links 54. The bell crank lever 53 operates in opposition to a spring 55 bearing against the inner arm of the lever. A cam 56 is carried by the shaft 8, said cam 55 56 contacting with the free end of the bell crank lever 53. As the shaft 8 rotates the bell crank lever 53 is rocked and, through toggle link connection with the stem 52, the diaphragm is actuated. When the toggle 60 links are drawn downwardly, the downward movement induced thereby on the diaphragm causes a suction in the upper part of the pump chamber drawing fuel from the chamber 47 into the pump chamber. When the diaphragm is forced outwardly the contents of 65

the chamber 48 is expelled through a valve 57 to the fuel delivery passage 14.

It is obvious that with this construction of pump constant lubrication of the connection between the bell crank lever 53 and the 70 cam 56 is required for efficient operation, and this is accomplished by the air continually supplied with oil through the pipe 42 when the apparatus is in operation.

I am aware that the invention may be 75 modified in certain particulars without departing from the spirit and scope thereof. I do not limit myself unessentially, but what I claim and desire to secure by Letters Patent is:—

80 1. In an apparatus of the class described, a pump, an oil sump, an oil inlet for the pump leading from the sump, an air supply from the pump, a chamber into which the air supply discharges, an air outlet for said chamber, a baffle located between the air inlet and outlet, a float in said chamber, and a discharge passage controlled by said float leading to said sump.

90 2. In an apparatus of the class described, a pump, an oil sump, an oil inlet for the pump leading from the sump, an air supply from the pump, a chamber into which the air supply discharges, an air outlet for said chamber, a baffle located between the air inlet and outlet, a float in said chamber, a discharge 95 passage controlled by said float leading to bearings in the apparatus requiring lubrication, and means to convey the oil from the bearings to the sump.
